ATTORNEY

John B. Borden
WITNESS:

UNITED STATES PATENT OFFICE.

FRANCIS DE GRUCHY, OF NEWARK, NEW JERSEY.

GRATE.

Application filed May 10, 1924. Serial No. 712,386.

To all whom it may concern:

Be it known that I, FRANCIS DE GRUCHY, a citizen of United States, residing at Newark, in the county of Essex and State of New Jersey, have invented new and useful Improvements in Grates, of which the following is a specification.

This invention relates to grates and more particularly to stoker grates for furnaces.

10 The principal object of the invention is the provision of a grate consisting of a plurality of identical grate sections arranged side by side and co-acting with each other to form air pockets beneath the upper 15 surfaces thereof, there being openings provided between the grate sections and grooves communicating with the openings to spread the draft of air from the air pockets when passing through the openings to assure a 20 complete consumption of the fuel carried upon the upper surface of the grate sections.

Another object of the invention resides in the provision of a grate section which is cast in a single piece and wherein a relatively 25 small opening is formed between the grate sections when the same are in assembled position to permit the burning of fine coal without fear of the coal passing through the openings on the supporting grate bar.

30 With these and other objects in view, the invention resides in certain novel construction and combination and arrangement of parts, the essential features of which are hereinafter fully described, are particularly 35 pointed out in the appended claim, and are illustrated in the accompanying drawing, in which:

Figure 1 is a side elevation of my improved grate section applied to the grate 40 bar of a stoker.

Figure 2 is a perspective view of a plurality of grate sections arranged in assembled position.

Figure 3 is a transverse sectional view on 45 the line 3—3 of Figure 1.

Figure 4 is a transverse sectional view of one of the grate sections per se.

Referring more particularly to the drawing, the reference numeral 10 designates the 50 grate bar of a stoker grate, and 11 a dovetail track bolted or otherwise removably secured to the grate bar 10 as at 12. My improved grate section is designated by the numeral 13 and which is substantially T-shaped in cross section to include a head

14 and a central longitudinal web 15 which extends the length of the head. The web 15 is provided with bosses 16 extending from opposite sides thereof and which bosses terminate in vertical alignment with the sides 55 of the head 14. The bosses 16 are formed, with transverse grooves 17 of a shape to be slidably received on the track 11. The grate sections are applied to the track by passing the same onto the track at one end thereof and sliding them to their proper position. Each grate section at one end thereof is formed with a lip 18, and a shoulder 19 which is disposed above the lip, and has its other end cut as at 20 for co-action with the 60 shoulder 19 of the next following grate section. The lips are adapted to prevent ashes from passing between the grate sections and falling onto the grate bars when the sections pass over the usual sprockets 65 at the ends of the stoker. The side edges of each grate section are provided with vertical semi-circular slots 21, the slots on one edge being arranged diametrically opposite to the slots on the other edge, and each slot 70 is flared at its top and bottom as at 22 and 23 respectively. Inclined grooves 24 communicate with the flared walls 22 and which grooves terminate short of the longitudinal center of the head and as clearly shown in 75 Figures 2 and 3 of the drawing.

In practice, the grate sections are arranged side by side on the grate bar so that the sides of the head and the bosses are flush against each other, whereby the semi-circular slots of one section co-act with the next adjacent section to provide a complete aperture or opening 25. When in this position, the webs 15 of the sections co-act to form the walls of air ducts 26 for trapping the force of draft from the air blast usually employed in connection with stoker grates and which is usually disposed below the grate bars. It will be seen that fine coal resting upon the upper surface of the grate 80 sections will be completely consumed or burned by reason of the air passing through the restricted portion of the openings 25, from the pockets 26 where the air is collected and then passing transversely toward the longitudinal center of the head through the inclined grooves 24. The air from the grooves 24 of one side of the head meets the air from the grooves diametrically opposite at approximately the center of the 85 90 95 100 105 110

head to assure a proper distribution of the draft over the grate surface. The air passing out of the flared portions 22 meets at the transverse center between longitudinal 5 rows of openings and affords a complete consumption at these points. From the description it will be manifest that a relatively fine fuel may be used in connection with a grate made up of grate sections such as have 10 been described, as the air is first trapped in the pockets beneath the upper surface of the grate, it is then passed through the restricted openings under a relatively high pressure sufficiently to prevent the coal from 15 passing through the opening.

While I have described what I deem to be the most desirable embodiment of my invention, it is obvious that many of the details may be varied without in any way 20 departing from the spirit of my invention, and I therefore do not limit myself to the exact details of construction herein set forth nor to anything less than the whole of my 25 invention limited only by the appended claim.

What is claimed as new is:—

In combination with the grate bar of a stoker grate, a plurality of grate sections arranged side by side, means for removably securing said sections to said grate bar, each 30 grate section including a head and a longitudinal web depending centrally therefrom, the web of one grate section co-acting with the web of the next adjacent grate section to define pockets, vertical slots diametrical- 35 ly arranged on the side faces of said head, the upper and lower walls of said slots being bevelled in opposite directions the slots of one grate section co-acting with the slots of the next adjacent grate sections to define 40 openings in communication with said pockets and the upper surface of the grate sections, and grooves formed in the upper face of the head and leading from the upper bevelled 45 walls of said slots toward the center but terminating short thereof substantially as and for the purpose specified.

In testimony whereof I have affixed my signature.

FRANCIS DE GRUCHY.
